ICE CUBE MAKERS

Carlyle M. Ashley, Fayetteville, N. Y., assignor to Carrier Corporation, Syracuse, N. Y., a corporation of Delaware

Application July 1, 1950, Serial No. 171,621

15 Claims. (Cl. 62—4)

This invention relates to devices for forming small pieces of ice and more particularly to a device for forming ice cubes for use in restaurants, bars, hotels or similar places in which a large quantity of small pieces of ice is consumed within a short period of time. The term "cube" is employed herein to define a small piece of ice of any desired geometrical configuration and is not limited to a piece of ice of specific geometrical contour.

The chief object of the present invention is to provide an ice cube maker in which the ice forming elements are designed to form separate pieces of ice of predetermined size and geometrical contour.

An object of the present invention is to provide an ice cube maker in which separate pieces of ice are formed periodically in vertically extending tubes, the separate pieces of ice when formed of desired size being automatically melted from the walls of the tubes and transferred to a storage chamber.

A further object is to provide an ice cube maker adapted to form transparent, separate pieces of ice in vertically extending tubes from a stream of water flowing through the tubes and including mechanism for rendering the machine wholly automatic in operation whereby the ice forming and harvesting operations are conducted cyclically until a desired quantity of ice is formed and then the operation of the machine is discontinued, operation commencing again automatically when a predetermined portion of the formed pieces is consumed.

A still further object is to provide a piece of ice so formed as to increase greatly the area thereof adapted to be placed in heat exchange relation with a liquid to be cooled thereby decreasing the time required to cool the liquid. Other objects of my invention will be readily perceived from the following description.

This invention relates to an ice cube maker comprising, in combination, at least one hollow ice forming element, a plurality of bands having a heat conductive value greater than the element placed in spaced relation to each other and in contact with the exterior of the element, means to direct a stream of water through the hollow element in contact with the interior wall of the element, a refrigeration system including an evaporator placed in heat exchange relation with the bands to form spaced pieces of ice within the interior of the element, and means to harvest the formed pieces of ice. Automatic control mechanism is provided to regulate the ice forming and harvesting operations as well as to discontinue and resume operation of the machine upon the formation of a desired quantity of ice and its consumption.

This invention further relates to a piece of ice having a predetermined exterior contour and having an opening extending through the piece from one side thereof to the opposite side permitting access to the interior of the ice piece of a liquid to be cooled, the interior wall of the ice piece surrounding the opening being so formed

as to provide an hour glass configuration to the opening.

The attached drawings illustrate a preferred embodiment of my invention, in which

5 Figure 1 is a front view partly in elevation and partly in section of the device of the present invention;

Figure 2 is a plan view, the casing being removed, of the device shown in Figure 1;

Figure 3 is a view in elevation, the casing being removed, of one side of the device;

10 Figure 4 is a view in elevation, the casing being removed, of the opposite side of the device;

Figure 5 is an isometric view of the ice forming element assembly;

15 Figure 6 is an isometric view of one ice forming element, showing the construction thereof;

Figure 7 is a diagrammatic view of the refrigeration circuit;

Figure 8 is a diagrammatic view of the water circuit;

20 Figure 9 is a diagrammatic view of the electrical circuit for the controls; and

Figure 10 is a sectional view of an ice cube formed in accordance with the present invention.

Referring to the drawings, there is disclosed the ice cube maker of the present invention which includes a

25 machine compartment 2 and an insulated ice storage compartment or bunker 3 placed below the machine compartment. Preferably, these compartments are formed as

separate elements, being attached to one another when the ice cube maker is assembled at the place of use in

30 order that the machine compartment may be utilized with bunkers of different capacity. It will be understood, of course, that the machine may be formed as a single unit if desired although such practice is not as satisfactory

commercially.

35 Machine compartment 2 includes standards 4 and braces

5 forming supporting framework. Decorated removable metal sheets 6 are attached to the frame to form the walls of the machine compartment. If desired, compartment 2 may be insulated to prevent condensation on the

40 surfaces of sheets 6. Storage compartment 3 is provided with an opening 7 through which ice enters the storage compartment 3 after its formation in machine compartment 2. Slidable lids 8 are provided to permit easy access to and removal of ice from compartment 3 for use.

45 The machine elements are placed and supported in compartment 2. Such elements include the ice forming members, the refrigerating and harvesting system, the water supply system, the controls and electrical circuit connecting the controls.

50 The ice forming member 9 includes a plurality of vertically extending tubes 10 formed of stainless steel or other low conductivity material, the tubes 10 having a

55 plurality of copper bands or rings 11 placed about the exterior thereof, the bands 11 being spaced from one another longitudinally of the tube. The copper bands may

be preformed and secured to the tubes by a friction fit or if desired molten copper may be sprayed on the tubes to

60 form the bands. The tubes 10 are assembled in two parallel rows and an overflow trough 12 is placed between the parallel rows for a purpose hereinafter explained.

65 Each tube 10 is formed from a single sheet of metal in such manner that its side walls 13 incline downward and outward substantially uniformly throughout the length of the tube so that the opening 14 in the bottom of the tube is greater in area than the opening 15 in the top of the

70 tube. Two adjacent side walls as shown in Figure 6 have flanges 16 and 17 extending outwardly therefrom, the flanges 16 and 17 being pressed together and spot welded, for example, to form the tube. The top of each tube is formed with a pitcher lip 18.

75 Preferably, each tube 10 is about seventeen inches in length and possesses an interior perimeter of about five

inches, the total inside area of each tube being about eighty-five square inches. The rate of conductance through the tube is approximately two B. t. u.'s per hour per square inch of inside area; at the portions of the tubes with which the bands are in contact, the rate of conductance is approximately eight B. t. u.'s per hour per square inch of band area. I have found that the rates of conductance described above permit most satisfactory results to be achieved. While such rates may be varied, it will be appreciated substantial variance prevents formation of spaced pieces of ice or renders the operation inefficient.

The evaporator 19 of the refrigeration system is formed of a plurality of coils 20, 21, 22, 23, coils 20, 21 being secured to the bands 11 on opposite sides of the first row of tubes 10 while coils 22, 23 are secured to the bands on opposite sides of the second row of tubes 10. If desired, coils 20, 21, 22, 23 may be flattened on one side to assure a greater area of contact with bands 11.

Below the ice forming member 9 is an inclined deflector or guide 24 on which the pieces of ice fall from tubes 10 during the harvesting operation and down which the ice slides into opening 7 of bunker 3. Deflector 24 may be a suitable screen or grid to permit water to pass therethrough while preventing passage of ice cubes. Water from the tubes passes through deflector 24 into a sump, as hereinafter explained.

Referring to Figure 7, there is shown the refrigerating and harvesting circuit of the ice cube maker. Such circuit includes a semi-hermetic compressor-motor unit, the compressor 28 being actuated by motor 29. Compressor 28 is connected by discharge line 30 to condenser 31, preferably water-cooled although if desired, an air cooled condenser may be employed. Liquid line 32 includes two capillary tubes 33, 34 adapted to serve as expansion means to regulate supply of liquid refrigerant to evaporator 19. A strainer 35 may be placed in line 32 between condenser 31 and capillaries 33, 34. Other expansion means may be employed if desired. Capillary 33 supplies refrigerant to coils 20, 21; capillary 34 supplies refrigerant to coils 22, 23. Refrigerant passes from each of coils 20, 21, 22, 23 into a return header 36 for return to compressor 28. Header 36 is connected by line 37 to accumulator 38. A line 39 connects accumulator 38 to a second accumulator 40. Accumulator 40 is connected by suction line 41 to the compressor 28. Accumulator 40 is also connected by a drain line 42 to the motor 29 to permit oil and liquid refrigerant in accumulator 40 to pass to the motor. This is an important feature since any liquid refrigerant draining from accumulator 40 with the oil is returned to the compressor 28 over the heated coils of the motor thus flashing the refrigerant to assure that gaseous refrigerant only returns to the compressor thereby avoiding excessive wear and tear of compressor elements.

Capillaries 33, 34 are wrapped about accumulator 38 in heat exchange relation therewith. In addition, the capillaries may be placed in heat exchange relation with line 39 if desired.

A heated refrigerant vapor line 43 connects the top of the condenser with a supply header 44 connected by lines 45 to the coils 20, 21, 22, 23. A solenoid valve 46 is placed in line 43 and closes the same to the passage of heated refrigerant vapor. It will be appreciated line 43 may connect header 44 with the compressor 28 or line 30 if desired, the requisite being that the refrigerant so supplied be heated in order that formed pieces of ice may be thawed or melted quickly from the interior walls of tubes 10.

In Figure 8, the water distribution system is shown diagrammatically. Line 50 conducts water from a source of supply (not shown) to a sump or reservoir 51 placed in the bottom of machine compartment 2 below tubes 10 and deflector 24. A float valve 52 regulates the level of water in sump 51. A drain line 53 serves to bleed a minor amount of water continuously from the sump thereby preventing concentration of minerals in the wa-

ter in the sump. A pump P circulates water from sump 51 through lines 54 to water headers 55 placed (refer to Figures 2 and 8) above the rows of tubes 10.

Water from headers 55 is discharged against distributors 56 placed within tubes 10, the distributors directing or guiding the water toward or against the interior walls of tubes 10. The water flows through tubes 10 in contact with the interior walls thereof, through deflector 24 and returns or falls into sump 51. The water, of course, is cooled by its passage through the refrigerated tubes 10 to substantially freezing temperature. Thus cooled or chilled water not formed into ice is continuously circulated through the tubes 10, thereby reducing the time required for ice formation and considerably increasing the capacity of the machine.

When passage of water through tubes 10 is prevented or retarded by the formation of ice therein, the tubes overflow, the lip 18 on each tube directing the water into trough 12 from whence it takes a different path to return to sump 51. The overflow water in trough 12 drains therefrom through a line 57 connected to an S-shaped pipe arrangement 58 which forms an overflow well. Water from well 58 returns to sump 51 through line 59. One leg 60 of overflow well 58 is clamped in contact with the heated refrigerant vapor line 43 of the refrigeration system for a purpose hereinafter explained.

To control the refrigeration and harvesting cycles, a wide differential thermostatic control 65 is provided which includes a switch 66 (refer to Figure 9) actuated by a thermal responsive system including a bellows 67 connected to the switch lever 66 and a capillary tube 68 connecting the bellows 67 with a bulb 69. The thermal responsive system contains a temperature responsive fill. Bulb 69 is placed in overflow well 58 and a portion 68' of capillary tube 68 is placed in contact with the suction line 41. Preferably, portion 68' is placed in contact with the portion of suction line 41 adjacent compressor 28 to assure that it is affected as little as possible by liquid refrigerant flooding back to the compressor 28 if such flooding back occurs. During the refrigeration cycle, thermostat 65 is governed by portion 68' in contact with suction line 41 since that is the coldest portion of the thermal responsive system and the fill condensate collects in portion 68'. When, however, water overflows from trough 12 into well 58, it displaces water present in the well and gradually cools bulb 69 until it becomes the coldest point of the thermal responsive system thereby governing thermostat 65 from such point rather than capillary tube portion 68'. Switch 66 is accordingly moved from a first position to a second position to discontinue operation of pump P and to actuate the solenoid S of valve 46 to open the heated refrigerant vapor line 43 to supply heated refrigerant vapor to coils 20, 21, 22, 23 to thaw formed pieces of ice from the interior walls of tubes 10. During the harvesting operation, the hot gas line 43 warms the water in the well 58 so that the control point again shifts to portion 68' of capillary tube 68 which is in contact with the suction line 41. Refrigerant passing through the suction line is below the cut-in point of thermostat 65 so long as ice remains in tubes 10. As soon as the last piece of ice is removed from tubes 10, temperature in the suction line rises and the thermostat is again actuated to start pump P and to discontinue current flow to solenoid S thereby closing valve 46 and resuming the refrigeration cycle.

A second normally closed thermostat control 70 is provided to discontinue operation of the refrigeration system and the pump when a desired quantity of ice is present in the bunker. Control 70 includes a switch lever 71, a bellows 72 connected by capillary tube 73 to a bulb 74 placed in the bunker 3 adjacent the top thereof. A suitable fill is present in bellows 72, capillary tube 73 and bulb 74. When a predetermined quantity of ice is present in bunker 3, bulb 74 is cooled thereby actuating thermostat 70 to open the circuit to control 65 and the com-

pressor, discontinuing operation of the system. Upon removal of ice from bunker 3, bulb 74 warms to a point at which thermostat 70 is again actuated to close the circuit, permitting supply of current to actuate the compressor and control 65.

Preferably, a high pressure cut-out control 75 is provided as a safety control, control 75 being responsive to head pressure to shut down the system upon the occurrence of a pressure so high that it might harm elements of the system.

In Figure 9, I have shown the electrical circuit connecting the various controls and actuating elements of the device. A manual switch 76 is employed to actuate the device. The remaining elements are connected in the circuit as shown.

The refrigeration system and controls are more fully described and claimed in the copending application of David E. MacLeod, Serial No. 171,593, filed July 1, 1950, to which reference is made for a complete description.

Considering the operation of the device, manual switch 76 is closed thereby actuating motor 29 to operate compressor 28 of the refrigeration system and pump P to supply water from sump 51 to headers 55 for distribution in tubes 10. Water flows downward over the interior walls of tubes 10 and returns to sump 51. The walls of tubes 10 are refrigerated at spaced portions by means of coils 20, 21, 22, 23 and the copper bands 11. Thus water flowing through the tubes is cooled and within a short time ice begins to form within the tubes adjacent the refrigerated portions thereof. As ice formation continues, within a short time, the spaced pieces of ice present in the tubes are so large as to impede or retard passage of cooled water therethrough so that the tubes overflow into trough 12.

Water from trough 12 flows through line 57 into overflow well 58 displacing the water therein and cooling bulb 69 so that it becomes the control point rather than capillary portion 68'. When a predetermined low point is reached, thermostat 65 is actuated moving switch lever 66 from a first position to a second position discontinuing operation of pump P and passage of water to tubes 10, and actuating solenoid S to move valve 46 to an open position permitting heated refrigerant vapor to flow into coils 20, 21, 22, 23 to thaw the formed pieces of ice from the interior walls of the tubes 10. Simultaneously, water in well 58, being in heat exchange relation with line 43, is heated to shift the control point of thermostat 65 to capillary portion 68'.

Capillary portion 68' does not become sufficiently warm to actuate the thermostat 65 until all ice is removed from the tubes 10, since it is in heat exchange relation primarily with liquid refrigerant condensed by heat exchange of the heated vapor with the formed ice in the tubes 10.

Ice drops from the tubes 10 by gravity upon deflector 24 and slides into bunker 3. As soon as the last piece of ice is removed from the tubes, the hot vapor passing into line 41 raises the temperature thereof thereby actuating thermostat 65 to move from its second position to its first position, closing the solenoid valve 46, resuming refrigeration of tubes 10 and starting pump P to supply water from sump 51 through tubes 10. The refrigerating and harvesting cycles repeat automatically until a predetermined quantity of ice is formed. When a predetermined quantity of ice is collected in bunker 3, thermostat 70 is actuated to break the electrical circuit discontinuing operation of the machine. Upon removal of ice from bunker 3, thermostat 70 is again actuated to begin operation of the machine.

The piece of ice formed by the present machine is designed for rapid cooling of the liquid in which it is placed. Referring to Figure 10, there is shown a transparent cube of ice formed by the present machine. The cube may be of any desired contour depending upon the shapes of tubes 10 and has a circular opening 81 extending therethrough from one side of the cube to its opposite side to provide

access to the interior of the cube of the liquid being cooled. The interior walls 82 of the cube 80 are so formed as to provide an hour glass configuration to the opening; in other words, when viewed in section the interior walls of the cube form oppositely opening parabolae.

The present invention provides an economical and easily operated machine for forming separate pieces of ice. The machine is particularly adapted for use in restaurants, 10 hotels, taverns, bars or the like in which a large quantity of small pieces of ice is consumed during daily operation. The machine so provided greatly decreases the cost of ice consumed in such places of use. The machine is simple and does not require more than occasional attention 15 since it is designed to operate automatically as required by the demand for pieces of ice. The ice forming elements are inexpensive and highly efficient in operation. The time required for forming and harvesting a desired quantity of ice varies, of course, with ambient temperature 20 and the temperature of the water supplied to the ice forming elements. The present invention permits the water supplied to the ice forming elements to be precooled thereby reducing the length of the refrigeration cycle and greatly increasing the capacity of the machine.

25 While I have described a preferred embodiment of my invention, it will be understood my invention is not limited thereto since it may be otherwise embodied within the scope of the following claims.

I claim:

30 1. In an ice cube maker, the combination of a hollow ice forming element, a plurality of bands substantially surrounding the exterior of the element and being placed in spaced relation to each other, said bands having a heat conductive value greater than the element, means to 35 direct a stream of water through the hollow element in contact with the interior wall of the element, a refrigeration system including an evaporator placed in heat exchange relation with the bands to form spaced pieces of ice within the interior of the element, and means to 40 harvest the formed pieces of ice.

2. An ice cube maker according to claim 1 including mechanism for discontinuing flow of water through the element during the harvesting operation.

3. In an ice cube maker, the combination of a stainless steel hollow ice forming element, a plurality of copper bands substantially surrounding the exterior of the stainless steel element and being placed in spaced relation to each other, means to pass a stream of water through the hollow element in contact with the interior wall of the element, a refrigeration system including an evaporator placed in heat exchange relation with the copper bands to form spaced pieces of ice within the interior of the stainless steel element, and means to harvest the formed pieces of ice.

4. An ice cube maker according to claim 1 in which the ice forming element is formed of a single metal sheet having each side formed at a substantially right angle to the adjacent side, two adjacent sides terminating in outwardly extending flanges in contact with each other 55 throughout the length of the element.

5. In an ice cube maker, the combination of a casing, a plurality of ice forming tubes placed adjacent one another in said casing, a plurality of spaced bands having a heat conductive value greater than the tubes placed 60 about the exterior of each tube, a sump in the casing, means to pass a stream of water from the sump through the tubes, the stream of water returning to the sump, a refrigeration system including an evaporator placed in heat exchange relation with the bands to form spaced pieces of ice from water flowing through the tubes, harvesting means, means to actuate the harvesting means, 65 a storage chamber for pieces of ice placed in a plane below the bottom of the tubes, and means to direct pieces of ice passing from the tubes to the storage chamber.

70 6. An ice cube maker according to claim 5 in which

the ice forming tubes are composed of stainless steel, the bands disposed thereabout being formed of copper.

7. An ice cube maker according to claim 5 in which the ice forming tubes are placed in two parallel rows, the evaporator including four refrigerant circuits, each refrigerant circuit being in contact with the bands on one side of the tubes in one row.

8. In an ice cube maker, the combination of a casing, a plurality of ice forming tubes placed adjacent one another in said casing, a plurality of spaced bands having a heat conductive value greater than the tubes, said spaced bands being placed about the exterior of each tube, a sump in the casing, a pump to pass a stream of water from the sump through the tubes, the stream of water returning to the sump, a refrigeration system including a compressor, a condenser, expansion means and an evaporator disposed in a closed circuit, the evaporator of the refrigeration system being placed in contact with the bands, a line connecting the evaporator with the discharge line of the circuit and means normally closing said line, opening of said means permitting heated refrigerant vapor to pass to the evaporator to harvest ice formed in the element.

9. In an ice forming element for an ice cube maker, the combination of a plurality of vertically extending tubes through which a stream of water is directed, a plurality of spaced bands surrounding the tubes, the bands having a greater rate of conductivity than the tubes, and an evaporator of a refrigeration system comprising a plurality of coils placed in contact with the bands to form spaced pieces of ice within the interior of the tubes.

10. In an ice forming element for an ice cube maker, the combination of a plurality of vertically extending stainless steel tubes placed in adjacent rows through which a stream of water is directed, a plurality of spaced copper bands surrounding the tubes, an evaporator of a refrigeration system comprising a plurality of coils placed in contact with the bands on opposite sides of a row of tubes to form spaced pieces of ice within the interior of the stainless steel tubes, expansion means for feeding refrigerant to the coils, and a header connected to each coil to supply heated refrigerant vapor to each coil to harvest formed ice.

11. An ice forming element according to claim 10 in which the expansion means comprise two capillary tubes, each capillary serving to feed liquid refrigerant to two coils.

12. In a process of forming ice, the steps which consist in directing a stream of water through a plurality of ice forming elements, forming spaced pieces of ice in each element from the water flowing through the elements by refrigerating spaced portions of the elements, and then when ice formation impedes substantially flow of water through the elements, discontinuing refrigeration of the spaced portions and flow of water to the elements and heating the spaced portions to free the ice pieces from the elements, removing the ice pieces from the ele-

ments, and when the ice pieces are removed, discontinuing heating of the spaced portions and resuming refrigeration thereof and flow of water through the elements, and automatically repeating the process cyclically until a desired quantity of ice pieces is formed.

13. In a process of operating an ice cube maker, the steps which consist in directing a stream of water through a plurality of hollow vertically extending tubes having spaced bands about their exteriors, forming spaced pieces of ice in the tubes from the water flowing through the tubes by refrigerating spaced portions of the tubes at the bands, discontinuing refrigeration of the spaced portions when flow of water through the tubes is impeded substantially, heating the tubes to harvest the ice pieces, collecting the pieces, discontinuing heating of the tubes, when the ice is harvested, again refrigerating the tubes, and automatically repeating the process cyclically until a desired quantity of ice pieces is collected.

14. In an ice cube maker, the combination of a hollow ice forming element, a plurality of bands having a heat conductive value greater than the element placed in spaced relation about the exterior of the element, means to direct a stream of water through the hollow element in contact with the interior wall of the element, a refrigeration system including an evaporator placed in contact with the bands to form spaced pieces of ice within the interior of the element, said element and bands being so constructed and arranged as to possess a rate of conductance of approximately two B. t. u.'s per hour per square inch of interior area of said element, and means to harvest the formed pieces of ice.

15. An ice cube maker according to claim 14 in which the rate of conductance through the element at the bands is approximately eight B. t. u.'s per hour per square inch of band.
